WIRE TERMINAL LUG

Marvin B. Nieman, St. Louis, Mo.

Application February 11, 1935, Serial No. 5,921

3 Claims. (Cl. 173—269)

My invention relates to terminal lugs or clips for electrical conductors, and more particularly to such lugs or clips formed of sheet metal.

One object of my invention is to provide a sheet metal terminal lug of relatively simple and convenient form, one portion thereof comprising a pair of sleeves arranged in spaced relation side by side and being pierced intermediate of these sleeves by an aperture for engaging a binding post of a terminal, and another portion thereof, longitudinally spaced from the first mentioned portion, comprising a pair of laterally disposed tabs adapted for folding over and down upon the insulated ends of a pair of electrical wires or conductors for connecting same to the terminal lug, the stripped ends of the said wires being inserted within the said sleeves and locked in place by turning down the nut of the binding post thereupon. Another object of the invention is to provide a sheet metal terminal lug or clip, one portion thereof comprising three folds or thicknesses of the metal forming a pair of laterally spaced sleeves for engaging the stripped extremities of a pair of electrical wires, there being an intermediate aperture for engaging a binding post of a terminal, and the other and longitudinally positioned portion of the same lug comprising a pair of laterally spaced tabs adapted for folding over inwardly and down upon the insulated ends of the said wires immediately back of the stripped ends thereof for protecting that insulation, whereby the said wires may be firmly and electrically connected to the said terminal. Still another object is to provide a form of metal blank or blank of any suitably conductive material adapted for conveniently forming up into a pair of laterally spaced sleeves for engaging the stripped ends of a pair of electrical wires, with an aperture for engaging a binding post formed between the sleeves, and a pair of separate and laterally spaced sleeves longitudinally aligned with the first named sleeves and adapted for engaging the insulation covered portions of the said wires immediately back of the stripped ends thereof.

With foregoing objects and advantages in view, attention is directed to the several structural features of the invention and its adaptation in use, as exemplified in one preferred embodiment thereof illustrated in the accompanying drawing, and wherein:

Figure 1 is a top plan view showing a terminal lug made in accordance with my invention, as mounted upon an instrument board for the pur-

pose of electrically connecting a pair of conductors to that board.

Figure 2 is a similar view of the terminal lug of Figure 1 shown detached from the instrument board and its terminal, the ends of two wires or conductors being shown as engaged thereby.

Figure 3 is a side elevation of the detached terminal lug, the subject matter of my invention.

Figure 4 is a section on the line 4—4 of Figure 3.

Figure 5 is a section on the line 5—5 of Figure 3.

Figure 6 is a diagrammatic or plan view of a blank well adapted for forming up so as to effectually embody and provide the constituent parts and elements of a terminal lug or clip made in accordance with my invention.

In practising this invention I provide a blank as indicated generally at 10 in Figure 6, the same being made of any suitably conductive material, such as metal, and including a medial section or fold 11 and lateral sections, folds or wings 12 and 13, which are designed to fold inwardly upon the medial section, as shown in the other views of the drawing, to form the completed device. The three sections, 11, 12 and 13 are demarcated or laid out to extend longitudinally of the blank, as indicated in the dotted lines in Figure 6, and are of approximately equal area. As thus demarcated the three sections are seen to be of an elongated form, so that when they are folded together they form the substantially elongated terminal lug or clip indicated generally at 14 in Figures 1, 2 and 3. The blank 10 is further demarcated at opposite sides, at substantially medially aligned points, by incisions or notches 15 extended substantially half-way thru the outer sections 12 and 13, on a line extending transversely of the blank. The aligned side portions 16 of the blank, as defined at one side of the notches 15, are extended somewhat beyond the side portions 17 at the other side of said notches, for a purpose later to be pointed out. The side portions 16 of the sections 11, 12 and 13 are pierced with aligned apertures 18, so spaced and located upon a line extended transversely of the blank, that when the sections are rolled over and folded down together for the purpose of bringing these apertures into registry as shown in Figure 5, for forming in the completed device the medial binding post aperture 18a, there will be also formed and provided the laterally disposed wire engaging sleeves 16a, one at either side of the aperture 18a, adapt-

ed for engaging the stripped extremities 20a of the electrical wires or conductors 20, normally covered by the insulation 20b. Similarly the free marginal portions or tabs 17 may be rolled over inwardly to form the sleeves 17a for engaging the insulation covered ends 20b of the said wires, immediately back of the stripped extremities, thus protecting the insulation at those points and co-operating with the sleeves 16a for locking the 10 wires in place within the lug.

In the manufacture of this lug or clip the two pairs of sleeves 16a and 17a are all preferably formed up ready for the free or loose insertion of the ends of the wires, in manner pointed out. 15 That is to say, these sleeves are formed slightly larger in diameter than the stripped portions and insulated portions, respectively, of the said ends, so that the ends may be inserted freely into place within the lug. In the use of the lug, after 20 the wire ends are first inserted in the manner pointed out, the sleeves are pinched tightly down onto the wire ends, thus locking them firmly in place. When this is done, the lug may be located upon the binding post 21 of the terminal 22 which 25 is secured by a screw 23 to the instrument board 24. This is accomplished by passing the binding post thru the aperture 18a of the lug, and turning down the nut 21a upon the threaded post, and tightly down upon the lug. In this operation 30 the nut preferably overlaps the sleeves 16a, as shown in Figure 1, whereby means is afforded for effectually pinching and pressing the walls of the sleeves inwardly upon the stripped ends of the wires for locking them in place and also 35 for insuring good electrical connection.

This device affords a simple and effective means for connecting a pair of wires to a terminal block or instrument board. It has other and varied uses however, as for connecting a pair of wires 40 to a single wire, or for connecting the parted ends of a broken wire. And while I have herein shown and described a certain embodiment of my invention and certain structural features thereof, it is understood that I may vary the structural 45 features of the invention so as best to adapt same to practical use, not departing however from the spirit and scope of the invention as defined in the appended claims.

I claim:

50 1. In a device of the kind described, a blank of conductive material dimensioned for demarking into three substantially parallel sections adapted for folding together upon the central section to form a terminal lug, the blank being notched at opposite edges substantially half thru 55

the outer sections, portions of the blank at one side of these notches being extended somewhat beyond the portions at the other side of the notches, the portions of the sections at the extended side of the blank being pierced with apertures so spaced and located in alignment, that when the three sections are rolled and folded together for bringing the said apertures into registry there will be also formed two laterally disposed wire engaging sleeves for engaging the stripped 10 extremities of a pair of electrical conductors and two somewhat larger sleeves longitudinally aligned with the first mentioned sleeves for engaging the adjacent insulation covered portions of those conductors immediately back of the 15 stripped ends thereof, whereby said first mentioned sleeves will be positioned against spreading by a binding post engaged in the apertures and will be clamped by a means carried by the binding post. 20

2. A wire terminal lug formed of a blank of sheet metal notched at opposite edges and foldable transversely of a line passing through said notches into three approximately equal sections, the resulting portions of the blank at one side of 25 the defining notches being rolled over and folded down upon the medial section, said medial section having an aperture therethrough, each fold having an aperture therethrough, said apertures being aligned to form a three-fold binding post 30 end with sleeves at the bights of the folds for engaging the stripped extremities of two wire conductors, the said sleeves being held against spreading by a binding post engaged in said apertures and the end portions of the blank at 35 the other side of the defining notches being rolled and folded down over upon said medial section to form sleeves for engaging the insulation covered ends of the wires immediately back of the said stripped extremities thereof. 40

3. A terminal lug of sheet metal, one end thereof comprising three superimposed folds of metal, each fold having an aperture therethrough, said apertures being aligned to engage a binding post, there being a pair of relatively small sleeves provided at the bights of the folds for engaging the stripped extremities of wires, and held against spreading by the engaged binding post and back of said pair of sleeves a pair of integrally connected, laterally spaced and relatively large 45 sleeves longitudinally aligned with the aforesaid smaller sleeves, for engaging the insulation covered portions of the wires immediately back of the stripped extremities thereof. 50
